PACKAGING DEVICE

William J. Kearney, 1430 S. 11th Ave., Maywood, Ill.
Filed Apr. 10, 1961, Ser. No. 102,024
1 Claim. (Cl. 229—51)

This invention relates to a packaging device and, more particularly, to a device adapted to be sealed in the first instance and thereafter repeatedly opened and closed.

The problem which the instant invention solves can be most readily visualized in terms of the cartons employed by hardware stores for containing nuts, bolts, screws, etc. Such cartons or containers must be repeatedly opened and closed, i.e., the top closure or flap must be opened a number of times to dispense only a portion of the contents each time. In the past, the achievement of this characteristic or advantage has been attended by a corresponding disadvantage in that the carton was inadequately or inconveniently sealed at the outset—as where it was shipped from the original manufacturer.

Manifestly, it would be desirable to have the container absolutely closed up to the time it reaches the hardware merchant to insure against accidental loss of contents, pilfering, etc. It would also be desirable to provide a container constructed so that the condition of its seal (broken or unbroken) may be determined at a glance. Heretofore, the attainment of all of these features, a container having a readily observable seal at the outset and an easily openable and re-closable closure element after the initial seal has been broken, has been difficult of attainment—and the provision of a device embodying these characteristics therefore constitutes a major objective of this invention.

Another object of the invention is to provide a container equipped with a closure flap that at the outset is anchored to the exterior of the container but subsequently may be inserted into the container as a temporary or easily openable flap or closure.

Still another object is to provide a container equipped with a top closure flap capable of being adhesively united to the container exterior at the outset but wherein the adhesively anchored portion is readily detachable to provide a convenient insertable type flap.

Other objects and advantages of this invention may be seen in the details of construction and operation as set down in this specification.

The invention will be explained in conjunction with the accompanying drawing in which—

FIG. 1 is an elevational view of a blank which may be employed in constructing a device incorporating the teachings of the invention;

FIG. 2 is an enlarged perspective view, partially broken away, of a container device developed from the blank of FIG. 1 and shown in a condition prior to filling and closing or sealing;

FIG. 3 is a perspective view of the container of FIG. 2 but with the container closed;

FIG. 4 is an enlarged sectional view of the container of FIG. 3 as would be used along the sight line 4—4 of FIG. 3;

FIG. 5 is a fragmentary perspective view essentially similar to FIG. 2 but in which the container has been opened after having been sealed according to the showing in FIG. 3;

FIG. 6 is a fragmentary perspective view showing the container temporarily closed and with the inner flap retained and left exposed as an indication of the fact that the container's original seal has been broken;

FIG. 7 is an elevational view of the blank analogous to that seen in FIG. 1, but which may be conveniently

2

employed for developing a modified form of container, i.e., a flatter container such as an envelope; and

FIG. 8 is a perspective view of an envelope type container such as would be constructed by variously folding and securing portions of the blank of FIG. 7.

5 In the illustration given, and with particular reference to FIG. 2, the numeral 10 designates generally a rectangular solid-shaped container wherein the front wall is designated by the numeral 11, the rear wall by the numeral 12, the parallel side walls by the numerals 13 and 14. The bottom wall is designated by the numeral 15 and the sixth or top side of the container is closable by an outer flap generally designated 16.

10 The outer flap 16 is seen to be connected to the rear wall 12 as at 17, the numeral 17 also designating a fold line in the flap whereby the flap 16 is adapted to be folded through a 90 degree angle to the position designated 16a in FIG. 4 and 16b in FIG. 6. The flap is equipped with an additional fold line—as by scoring, which is designated by the numeral 18, the fold line 18 being spaced between the fold line 17 and the free edge 19 of the flap. The spacing between the parallel fold lines 17 and 18 corresponds essentially to the thickness of the container 10 and as such constitute a well known construction, permitting the flap to be positioned against the front wall 11.

15 Spaced between the fold line 18 and the free edge 19 is a line of weakness or potential severance 20 provided as by perforation. In FIG. 5 this is seen to be the "new" free edge of the flap 16. The inside of the flap 16 is equipped with an adhesive 21 between the severance line 20 and the free edge 19. A like adhesive is provided at 22 (designated only in FIG. 1) on the outside of the front wall 11 so that the flap adhesive portion 21 is mateable therewith to achieve the configuration seen in FIGS. 3 and 4. This would be the condition, i.e., the condition of FIGS. 3 and 4 of the package or container 10 during shipment. Thus, the goods are maintained within the container 10 in a sealed condition. Upon arrival in the condition seen in FIGS. 3 and 4, the user merely need insert a fingernail or letter-opener type tool underneath the flap portion generally designated 23 in FIGS. 3 and 4, whereupon the flap portion covered by the adhesive 21 remains in contact with the front wall 11, the rest of the flap 16 being released and which is designated by the numeral 16c in FIG. 5.

20 The foreshortened flap 16c of FIG. 5 thereafter may be again folded along lines 17 and 18 to develop the configuration seen in FIG. 6 wherein the flap 16b is seen to be inserted interiorly of the container 10, i.e., between the front and rear walls 11 and 12, respectively. As such, the flap 16b of FIG. 6 may be repeatedly opened and closed to permit temporary access to the contents of the container 10.

25 The container 10 may be constructed in a variety of fashions and one form is illustrated in FIG. 1 wherein a blank or diecut sheet is illustrated. There the various fold lines and cut portions are designated by numerals analogous to those employed in connection with FIGS. 1—4. The blank itself is designated generally by the numeral 10a and is seen to include a generally rectangular sheet.

30 Optimum results are achieved when the inventive container is constructed of paperboard having a thickness or caliber in the range 0.014—0.040 inch. Preferably, a cohesive type adhesive is employed, that is to say, an adhesive that adheres primarily to itself, not to other surfaces, exemplary of this being latex rubber adhesives. The boxboard may be any suitable board material such as clay-coated board, bleached manila, etc. The weight or caliber of the board employed is dictated to a certain extent by the amount of weight the carton must support when it is stacked. When the envelope of FIG. 8 is uti-

lized, it is desirable to have the paperboard rigid enough so that the closure flap may be printed and the envelopes stand up when stacked so that the printing can be readily seen. For the larger containers, such as are illustrated in FIGS. 2-6, heavier calipers of board are employed. The heavier caliper boards also permit the utilization of greater perforation or weakness. For example, when the forty point board is employed (a caliper of 0.04 inch) it is possible to employ perforations $\frac{1}{32}$ " long spaced apart by bonds $\frac{1}{32}$ " long. The thickness of the board thus insures a satisfactory bond so that the portion carrying the adhesive 21 is not too readily detached from the flap itself. On the lighter caliper containers, I prefer to use perforations $\frac{1}{16}$ " long with the intervening bonds being of the order of $\frac{1}{16}$ ". On the very light envelope type containers, the perforations may be made even longer and spaced farther apart, as for example $\frac{1}{8}$ " long perforations spaced apart $\frac{1}{8}$ ". Here, however, it will be appreciated that other potential severance means may be employed such as scoring or other partial cutting.

Facilitating the detachment of the flap portion 23a which is equipped with the adhesive 21 are inwardly extending notches 24 (designated in FIGS. 1-3). The notches advantageously may be V-shaped with the apices of the V's determining the ends of the line of severance 20.

In the fabrication of the packaging device seen in FIGS. 2-6, a fibrous sheet may be cut to the configuration indicated in FIG. 1. In FIG. 1, it will be noted that a portion of the bottom wall 15a has been illustrated in broken away condition so as to show the presence thereon of a band of adhesive 25. The adhesive 25 mates with a corresponding band of adhesive 26 provided on a flap portion 15b, the adhesives 25 and 26 preferably being the same as the adhesive bands 21 and 22. The side wall 14 of the container 10 is developed from flap or wall forming portions 14a and 14b. Again, a portion of the flap 14a is shown in broken away condition, as at 14c, to illustrate the fact that there is a band of adhesive 27 applied to the reverse or interior side of the wall forming portion 14a. A corresponding band of adhesive 28 is provided on the flap 14b.

The blank 10a of FIG. 1 is also equipped with tab portions 29 and 30 which provide the side flaps correspondingly designated in FIG. 2. Also provided in the blank 10a is a detachable tab or inner flap designated 31. The tablike inner flap 31 is attached to the upper edge of the front panel 11, as at 32, this numeral also designating a line of perforation for detachment of the tablike flap 31. The line of perforation 32 includes a circular portion in the center, as at 33, which, when the flap 31 is removed results in the contour designated 34 in FIG. 5. Prior to removal of the flap portion 23a, the flap 31 provides a desirable reinforcement for the main flap 16, urging the same upwardly and maintaining the flap portion 23 essentially flat or flush against the front face 11.

The inner flap or tab 31 may be left attached to front wall 11 following the initial opening of the container (rather than being torn away along perforation line 32) and may be folded outwardly to provide a clear indication that the original seal of the container has been broken. As shown in FIG. 6, the tab 31 will not interfere with the movement of flap 16 into its temporarily closed position. If the merchant, after removing part of the container's contents and closing the flap in the manner shown, places the container on a shelf or some other supporting surface, the outwardly projecting tab will serve as a flag to indicate that the particular container holds only a split quantity of materials. The smooth surfaces of the tab may be used to bear notations applied by the merchant concerning the quantity of materials remaining in the container, or any other information concerning the package or its contents.

Referring now to FIGS. 7 and 8, a modification is illustrated and will be described herein employing numerals

5 4 like those employed in conjunction with FIGS. 1-6 but increased by 100. Thus, the numeral 110 as applied to FIG. 8 designates generally the container, while the numeral 110a applied generally to FIG. 7 designates the blank from which the container 110 is developed.

In FIG. 8, the openable flap is designated by the numeral 116 and is seen to be joined along one edge thereof, as at 117, to the rear wall 112 of the envelope-type container 110. A second fold line 118 is provided and adjacent the free edge 119 of the flap 116, there is provided on the interior of the flap 116 a band of adhesive 121. Extending parallel to the free edge 119 is a line of perforation 120, the ends of which are notched as at 124. The fold lines or creases 117 can be conveniently provided during the step of fabricating the blank 110a.

The front wall 111 of the envelope-type container 110 is made up of wall portions 111a and 111b (see FIG. 7). These flap portions are overlapped as at 111c (see FIG. 8). The bottom wall 115 is equipped with adhesive as at 115a which mates with adhesive 111d on the front panels 111a and 111b respectively (partially seen in FIG. 8). The bottom wall 115 is equipped with parallel creases 115b which in combination with the creases 113a and 114a provided in the side walls 113 and 114, respectively, permit the development of an accordion-type envelope. The central of the three creases in the groups 113a, 114a and 115b, is reversely formed from the other two to yield the V configuration plainly seen in the upper portion of FIG. 8.

The operation of the device seen in FIGS. 7 and 8 corresponds to that previously referred to in connection with FIGS. 1-6. At the outset, the top flap 116 will be positioned in covering relation with the front wall 111, the band of adhesive 121 mating with the band of adhesive 122 provided on the front wall 111. At such time, the envelope-type container may be filled with parts for shipment—generally parts which will ultimately be retailed or dispensed sequentially and at different times, necessitating opening and closing of the container. Illustrative of this might be gaskets where a large variety of sizes would have to be stocked. Several samples of each size would have to be available and these could all be packaged in one container 110. A legend denoting this would be applied to the outer side of the flap 116 between the lines 117 and 118. When the container 110 is received at the site of retailing, the container 110 is opened merely by severing the flap 116 along the line 120. This leaves the portion 123a remaining over the front wall 111 and in covering relation with the adhesive band 122. Thus, there is no exposed adhesive band on the front panel of the envelope. The container 110, in this condition, permits access to the interior thereof for the removal of an article to be retailed. Thereafter, the now foreshortened flap is insertable between the walls 111 and 112 (analogous to the fashion seen in FIG. 6).

In the form shown in FIGS. 7 and 8, I have not illustrated the envelope equipped with a tab of the type described in connection with the first embodiment as tab 31. It is to be understood, however, that such a tab may also be provided along the envelope's front edge to serve as an indication of split quantities, as previously mentioned in describing the view of FIG. 6.

While in the foregoing specification I have set forth a detailed description of embodiments of the invention, many variations in the details herein given may be made by those skilled in the art without departing from the spirit and scope of the invention.

I claim:

A blank adapted to form a package, comprising an elongated flexible fibrous sheet defining front and rear surfaces and equipped with a plurality of longitudinal and transverse fold lines defining first and second generally rectangular face panels for said package and a side panel therebetween and foldably connected to said face panels,

- (a) said first face panel having at one end a flap equipped with a cohesive latex adhesive extending over the front surface of said blank, said first face panel having at the other end a weakness line defining a tear-off flap, 5
- (b) said second face panel having at one end a flap twice the width of said first face flap and cooperable therewith to form a bottom end closure for said package, said second face panel flap being equipped with a stripe of cohesive latex adhesive along the flap free edge and on the rear surface of said blank, said stripe being the width of said first face panel flap and offset therefrom, 10
- (c) said first face panel having a second side panel extending therefrom along the side opposite the side connected to the first-mentioned side panel, said second side panel having an adhesive extending over the front surface thereof, 15
- (d) said second face panel having a second side panel extending therefrom along the side opposite the side connected to said first-mentioned side panel, the last-mentioned second side panel having a width twice the width of the first-mentioned second side panel and equipped with a stripe of adhesive having a width of said first-mentioned second side panel and disposed along the free edge thereof, 20 25
- (e) said second face panel having at the other end a second flap adapted to provide a top end closure for said package, said second flap having a pair of spaced weakness lines extending parallel to the free edge of said second flap, the line closer to said second flap free edge being a line of potential sever-

5

- ance while the other line is a fold line, the distance between said second face panel other end and said other line being equal to the width of said first-mentioned side panel, the area of said second flap between the first-mentioned line and said second flap free edge having a cohesive latex adhesive on the rear surface thereof,
- (f) said first face panel having a band of cohesive latex adhesive thereon adjacent and parallel to but spaced from the other end thereof, the spacing of said band from said first face panel other end being equal to the distance between said lines, said band having a width equal to the width of the adhesive on said second flap, and
- (g) tabs foldably projecting from the ends of said first-mentioned side panel and from the side panel associated with said second face panel, the tab extending from the one end of the side panel associated with said second face panel being equipped with cohesive latex adhesive on the front surface thereof.
